UNITED STATES PATENT OFFICE.

JOHN H. BEEBY, OF OTTAWA, ONTARIO, CANADA.

GAS BURNER.

Application filed October 8, 1921. Serial No. 506,535.

To all whom it may concern:

Be it known that I, JOHN H. BEEBY, a citizen of the United States of America, residing at Ottawa, in the county of Carleton and Province of Ontario, Dominion of Canada, have invented certain new and useful Improvements in Gas Burners, of which the following is a specification.

The present invention relates to improvements in gas burners adapted for use in gas, wood or coal stoves and particularly appertains to the exit opening of the said gas burner.

The principal object of the invention is to provide a burner having a spreader adjustably positioned at the discharge end thereof, which spreader acts as a protective member and is a controlling means for the egress of the combustive elements in the mixing chamber of said burner.

With these and other aims and objects in view, the invention consists in the construction, combination and arrangement of parts, as will be hereinafter fully described, illustrated in the accompanying drawings and pointed out in the claim hereunto appended.

The drawing illustrates in a fragmentary vertical medial section, a device constructed in accordance with the invention, certain parts being shown in elevation and sundry elements being indicated diagrammatically.

Referring to the drawings in detail, the numeral 1 indicates the body of the burner which is provided with an upset terminal as indicated by the numeral 2. This upset terminal 2 is provided with a conical seat 3. The numeral 4 indicates a spindle, the lower portion of which is threaded and passes through the lower portion of the burner 1. On the upper extremity of this spindle 4 I provide a conical spreader indicated by the numeral 5, the said spreader being invertibly positioned as indicated diagrammatically. In this spreader I provide a groove illustrated in dotted position and indicated by the numeral 6. This groove 6 provides a means whereby the operator, with the aid of screw driver, may adjust the spreader, in relation to the conical seat 3. The numeral 7 indicates a wing nut positioned on the spindle 4. The said wing nut is adapted to abut against the lower por-

tion of the burner 1, to rigidly lock the spreader in position when the same is properly adjusted.

The space between the spreader 5 and the seat 3 can be readily adjusted to adapt the burner for the consumption of any number of cubic feet of gas desired. When adjusted in the desired position, wing nut 7, threadedly engaged on the spindle 4, will hold the spreader fixedly in this adjusted position.

All other burners, which have been placed on the market, have a limited gas exit and, therefore, when a heavier volume of gas is to be used, a new burner with a larger opening has to be installed, while with my construction, the controlling means can be readily adjusted.

In all burners on the market, the exit openings are so constructed that if the contents in the cooking utensils boil over, the contents boiling over will fall into the exit opening. The exit opening soon becomes clogged and thus does not allow the proper discharge of combustive elements. In my construction, the spreader 5 entirely overhangs the exit opening and any substance will splash on the spreader and will not in any case enter the exit opening.

Perusal of the foregoing will manifest that the spreader is especially adapted for use with burners for coal or wood burning stoves. Although the exit opening will not be impervious to dust caused by the shaking of the stove, it will be apparent that the egress of the combustive elements will disperse with the same.

While it is believed that from the foregoing description, the nature and advantages of the invention will be readily apparent, I desire to have it understood that the same is merely illustrative of the preferred embodiment of the invention, to which I do not limit myself and that such modifications may be resorted to when desired as properly fall within the scope of the appended claim.

What I claim as new is:

In a burner, a means for controlling the egress of the air and gas mixture from the said burner, said controlling means consisting of a conical shaped spreader invertibly positioned in the exit of the said burn-

100
105

er, a rod having its upper end rigid with said spreader and its lower end screw threaded through the bottom of the body of the burner to form a means for positively spacing said conical shaped spreader in relation to the exit end of said burner, said conical shaped member having its outer face wider than the outer circumference of the said burner and a means for locking said

conical shaped member in fixed open and closed position when properly regulated.

In testimony whereof, I affix my signature in the presence of two witnesses.

JOHN H. BEEBY.

Witnesses:

H. P. ARMSTRONG,
M. McMILLAN.
